UNITED STATES PATENT OFFICE.

JEREMIAH CARHART, OF NEW YORK, N. Y.

MACHINE FOR PLANING METAL.

Specification of Letters Patent No. 24,792, dated July 19, 1859.

To all whom it may concern:

Be it known that I, JEREMIAH CARHART, of the city, county, and State of New York, have invented new and useful improvements 5 in machinery for planing metals, particularly applicable to smoothing and reducing to a uniform thickness and width thin pieces of metal; and the following is a full and clear description of the same, reference 10 being had to the accompanying drawings, which make part of the same, in which—

Figure 1, is a side view of my machine, Fig. 2, is a top view thereof, Fig. 3, is a cross section at line x, y , of Fig. 2, and Fig. 4 is a 15 cross section immediately in front of the cutters.

The operative machinery is supported by a firm bench of which l, l are the legs, and t, t , the top. Along the whole length of the 20 top of this bench, extend two strong flanches f, f , one near each longitudinal edge thereof, leaving a space between them. At the lower inner edges of these ribs are bevel grooves the whole length thereof, the lower side of 25 said grooves being formed by the upper surface of the bench t , as shown at g, g . In these grooves are placed the outer edges of a reciprocating bed b , nearly as long as the top of the bench and supported thereby 30 throughout. This traveling bed has a strong rib r , rising longitudinally along its middle and reduced in thickness laterally so as to pass between the edging cutters. This rib extends upward the proper height for 35 supporting the metal to be reduced and dressed. A reciprocating motion is given to the bed b , from the driving wheel W , the shaft S , the bevel gear G , the shaft S' , crank K , connecting rod R , and short arm a 40 which is firmly connected with the reciprocating bed and works through a slot in the top t of the bench.

At about two thirds of the distance from the crank end of the bench to the opposite 45 end, the cutter head H is placed, which is a strong block of iron extending across from flanch f , to flanch f and firmly bolted to said flanches giving them the proper support for sustaining the strain upon them by the operation of the machine, there is a groove in the 50 bottom of this block lengthwise of the machine, sufficient to allow the rib r , of the reciprocating bed, with the piece of metal planed, to pass freely. In the face of this 55 block toward the crank end of the machine are two horizontal grooves i, i for the side

cutters c , the edges of these which are on each side of the rib r , are nearly level with the top of the rib;—and in the same face of the cutter head, is a vertical groove i , directly over the said rib for the facing cutter c , the cutters are held firmly in their places in the grooves, each by a horizontal strap bolt extending to the opposite side of the cutter block and secured by nuts. 6

Directly in front of the cutters, and as near them as may be without obstructing the shavings, are the devices for guiding the metal to the cutters and holding it down firmly, while being dressed. These are as 7 follows: Upon the top of each of the flanches f, f , directly in front of the cutters, and opposite to each other, there are firmly bolted, strong plates of metal p, p , of length equal to that of the longest plate intended 7: to be planed, and of width such that they extend nearly to the rib, r , on the traveling bed, but having sufficient space between them for the said rib to pass freely between thereon; on the outer edges of these plates, 8 flanches rise up, through which from the outer side, set screws pass, horizontally and cross-wise of the machine, their inner ends being a little above the upper surfaces of the plates. Upon these plates inside of the 8: flanches thereon are placed two other strong plates of metal p', p' , of about equal length with plates p, p , and of such width as to nearly meet over the rib r , but leaving space for lateral adjustment by the set screws v, v . 9 The adjacent edges of these plates are rabbeted in such a manner as to receive the plate to be planed between them and nearly inclose it on the upper side and edges. 90

The plates p', p' , are held down upon the 95 plates p, p , by strong springs pressing against the bottom of the plates p, p , through a bolt passing up through openings in both plates, with a head at one end and a nut at the other, the openings for these bolts should 10 be elongated in the upper or lower plate transversely, to allow adjustment of the plates p', p' , by the set screws v, v , to adapt them to the width of the plates to be dressed.

Fig. 5 represents in section, the manner in 10: which the plates p', p' , are held down to the plate p, v being the screw bolt and s , the spring which is capable of adjustment and usually exerts a power of about five hundred pounds. And the depth of the 11 rabbets in the inner edge of the plates p', p' , are such that when the plate to be planed

passes through them, resting on the rib r , of the reciprocating bed; it (the plate to be planed) shall receive upon its upper surface the full pressure due to the springs s , while its edges are guided laterally by the vertical sides of the rabbets. For planing blanks, differing in dimensions, the plates p' , p'' , should be changed in adaptation thereto. As shavings and dust are liable to get in between the plates p' , p'' , a shield or apron a' is made to extend over the rabbets and from the plates p' , p'' to the bottom of the plate z . At the end of the rabbets, and just next the plate z , two cutters are set into the bed rib r , and from the bottom of the bed rib r , the rabbets are made slightly trumpet-mouthed, the more readily to admit the plate or blank to be dressed. Immediately in front of this apparatus for holding and guiding the blanks, is the hopper which holds them, and from which they are fed to the dressing apparatus; it consists of two strips of metal of a trough form, standing vertically with their hollow sides facing each other and directly over the bed rib r , said rib serving as a bottom. Both of these vertical parts are supported on either side by arms from the flanch f , and the arms sustaining one of them are so adjustable as to adapt the hopper to blanks of different lengths. The hopper is shown at h , h , the blanks are placed in it, one above the other, and are free to settle down, as the bottom blank is successively carried forward and dressed. Along the top of the rib r , toward the crank end, a thin strip of metal q , about the width of the top of the rib, is firmly bolted, the thickness and width of this strip are slightly less than those to be given to the blank by dressing, so that it can slide freely under and between the cutters. The length of this strip should be equal to the whole distance the reciprocating bed is made to move, and its back end should at each revolution, move entirely past the hopper and the cutters, but its forward end should never reach the hopper.

The operation of this machine is as follows, viz: The edge cutters are adjusted to the width to be given to the dressed blank, and at equal distances on each side from the rib r . The face cutter is adjusted so that the space between its edge and the upper surface of the rib r , is equal to the thickness to be given to the blank. The hopper is then filled with blanks and the belt B , slipped upon the tight pulley giving motion to the crank, which causes the bed plate b , with its rib r , to reciprocate. When the back end of the strip q , is drawn forward of the hopper the blanks sink down and rest upon the top of the rib r , but when it returns, the back end of the strip seizes the lowest blank and pushes it under the plates p' , p'' , and carries it entirely past the cutters

which dress it, and reduce it, to a perfectly uniform width and thickness. As the bed returns, the blanks in the hopper rest upon the top of the strip q , till its back end has passed the hopper, when they again sink down and rest upon the top of the rib r , as before, the lowest in position, to be taken by the back end of the strip at the next throw of the crank. The parts for dressing brass should move at such a rate as to plane about four inches per second, or very little faster. As it is indispensably necessary that the portion of the upper surface of the rib r , upon which the blank rests, should be cleaned from shavings or other foreign matter while the blank is being carried through the cutters, devices are necessary for cleaning it at each operation. For this purpose a sliding scraper is attached to the back of the hopper immediately in front of the pressure plates p' , p'' , the lower edge of which rests upon the top of the rib r , or strip q , according to the position of said rib, and as the carriage is drawn forward, the scraper slides down from the surface of the feeding strip to that of the rib and scrapes the foreign matter from it before the blanks fall upon it. But as the operation of this is insufficient to clean the surface immediately at the feeding end of the strip q , a brush is placed on the underside of the end of an arm a' , which is jointed at the front end of a cross bar c' . This arm a' , has attached to its forward end another arm a'' which is pushed back by a slight spring beneath, which holds the arm a' , on the right side of the rib, and also at the outer extremity of the arm a'' is another arm a''' extending downward, which when the carriage is completing its motion forward for taking another blank, is struck by a pin o , on the carriage and is carried forward a short distance, causing the brush to sweep across the rib at the feeding end of the strip, and when the carriage begins to move in the opposite direction, the arm being relieved from the pin is thrown back by the spring above mentioned and the brush is thus caused to sweep back across the rib, at the same point in an opposite direction, and the surface is thus perfectly cleaned, so that the blank will rest evenly on the top of the rib, to be carried through the guiding and pressing apparatus and the cutters.

At the front end of the machine (see Fig. 120) a stop n' , is placed on the left flanch f , a little back of the front cross-bar against which the arm a''' , strikes to limit the movement of the brush, a stop for this purpose might be placed on the other side of the machine as shown at n'' . At the other end of the machine and immediately behind the cutter head is a tube, in continuation of the groove in the cutter head block open at the bottom wide enough to allow the rib r , to

slide, but slightly narrower than the dressed strips of metal, for the purpose of guiding the latter out of the machine when finished. This tube is represented at t' , on the drawings.

It is obvious that the pressure plates may be made in one piece but I much prefer them as represented.

Having thus fully described my invention, 10 I claim,

1. The pressure plate or plates in combination with the reciprocating bed and feeding strip, when said plates, extend substantially the length of the blank to be 15 planed, and the bed travels far enough to carry the feeding end of the strip entirely past the facing cutter, at each operation, substantially as set forth.

2. I also claim rabbeting the inner edges

of the pressure plate or plates as described, 20 in such manner, as to furnish at once, edge guides and pressure for the blank while being fed to the cutters.

3. I also claim in combination with the pressure plates and cutters, the shields extending downward from the pressure plates 25 to protect the space between the plates, from shavings and other foreign matter, as described.

4. I also claim in combination with the 30 reciprocating bed and feeder, the scraper and brush acting in combination, for cleaning the bed and feeder or feeding strip, substantially as described.

J. CARHART.
